UNITED STATES PATENT OFFICE.

ANTHONY ZIER, OF CHICAGO, ILLINOIS.

COLLAR-FASTENER.

No. 893,692.

Specification of Letters Patent.

Patented July 21, 1908.

Application filed July 3, 1907. Serial No. 382,029.

To all whom it may concern:

Be it known that I, ANTHONY ZIER, a citizen of the United States, residing at Chicago, in the county of Cook and State of Illinois, have invented certain new and useful Improvements in Collar-Fasteners, of which the following is a specification.

This invention relates to means for attaching a collar to the neck-band of a shirt, and its objects are to make the device readily attachable to the collar and the neck-band; to permit of a sliding or self-adjusting connection between the fastener and the neck-band; to make the fastener flat and relatively thin; to provide means for holding the necktie in place; and in general to improve this class of devices with a view to convenience and security in use and cheapness of manufacture.

20 The accompanying drawings illustrate an embodiment of the invention, all of the views being considerably enlarged.

Figure 1 is a rear side elevation of one embodiment of my invention. Fig. 2 is an edge view thereof. Fig. 3 is a rear side view of the fastener attached to a collar. Fig. 4 is a front or inner side view of the fastener attached to the collar. Fig. 5 is an inner side view of the fastener in place upon the neck-band. Figs. 6 and 7 are side and edge views, respectively, of a modified form of the fastener.

The fastener may be made of wire or other suitable material, but is preferably made of sheet metal such as spring brass, and comprises a member 1 adapted for attachment to the collar *a*, and a member 2 adapted to be slipped into the collar-button pocket or double portion of the neck-band of the shirt. 35 The member 1 comprises two tongues 3 and 4 adapted to be passed through the button-hole *a'* of the collar *a* and to lie, one at the upper side and one at the lower side of said buttonhole and upon the rear or outer side of the collar. 40 The member 1 also comprises the two portions 5 and 6 adapted to lie at the upper and lower sides of the buttonhole *a'* upon the inner side of the collar.

The neck-bands of shirts are usually provided with a double portion or pocket, the buttonhole being in the outer thickness, so that the base of the collar button shall be enclosed in said pocket and thereby held out of contact with the neck of the wearer. In the

drawings, *b* indicates the inner wall of the 55 pocket or double portion, and *b'* the outer wall.

The member 2 of the fastener may be of any suitable form adapted for insertion into the double portion of the neck-band through 60 the open lower end of the pocket formed by the walls *b* and *b'*. The members 1 and 2 are united at their lower ends, as indicated at 7 in Fig. 1.

When used with the ordinary stand-up 65 collar it is desirable that means be provided for holding the necktie from upward displacement. I have herein shown a hook 8 formed integral with the tongue 3, said hook being adapted to receive the upper edge of 70 the tie. When the fastener is used with a turn-over collar it is obvious that such means need not be provided. Figs. 6 and 7 illustrate a collar fastener in which the hook 8 is omitted.

In use, the tongues 3 and 4 are inserted 75 through the buttonhole *a'* of the collar from the inner side of the latter. Said tongues, in conjunction with the portions 5 and 6, firmly 80 secure the fastener to the collar. The member 2 is then slipped into the pocket in the neck-band from the open lower end of said pocket, and the ends of the collar secured together in front in the usual manner. It will be seen that since the member 2 lies loosely 85 between the walls *b* and *b'* of the neck-band pocket, the fastener is free to adjust itself by sliding to either side within said pocket. When the collar is buttoned in place in front 90 the fastener is held from upward displacement with relation to the neck-band by the closed upper end of the pocket and from downward displacement by reason of the collar resting upon the base of the neck.

When engaged with the hook 8, the necktie 95 covers the tongues 3 and 4, the fastener, proper, thus being completely concealed.

It will be seen that I have produced a very simple and efficient fastener. Being relatively thin and consequently occupying but 100 little space, the fastener permits the vest and the coat collar to fit close to the collar.

It is obvious that various changes may be made in the embodiments herein illustrated without departing from the spirit and scope 105 of the invention, wherefore I desire to have it understood that I do not limit myself to the precise details herein set forth.

I claim as my invention:

1. A collar fastener comprising a member adapted to extend through the buttonhole of the collar and adapted to engage opposite sides of the collar at each side of the button-hole, and means to engage the neck-band.
2. A collar fastener comprising a member adapted to extend through the buttonhole of the collar and engage opposite sides of the collar at each side of the buttonhole, and a member adapted to lie loosely within the double portion of the neck-band.
3. A collar fastener comprising a relatively flat member adapted to extend through the buttonhole of the collar and engage opposite sides of the collar at each side of the button-hole, and a relatively flat member adapted to lie loosely within the double portion of the neck-band, said members being connected together at their lower ends.
4. A collar fastener comprising a relatively flat member adapted to extend through the buttonhole of the collar and engage opposite

sides of the collar; and a relatively flat member adapted to lie loosely within the double portion of the neck-band, said members normally lying in the same plane.

5. A collar fastener comprising a member adapted to extend through the buttonhole of the collar; tongues on said member adapted to lie at the upper and lower sides of the buttonhole, at one side of the collar; members adapted to lie at the opposite side of the collar, and means to engage the neck-band.

6. A collar fastener comprising a member adapted to extend through the buttonhole of the collar; tongues on said member adapted to lie at the upper and lower sides of the buttonhole at one side of the collar; a tie holding hook on one of said tongues; means adapted to lie at the opposite side of the collar; and means to engage the neck-band.

ANTHONY ZIER.
